Primary Examiner — Wan Laymon*Assistant Examiner* — Mark Booker(74) *Attorney, Agent, or Firm* — Oliff PLC(57) **CLAIM**

The ornamental design for a guidewire for a medical device, as shown and described.

DESCRIPTION

FIG. 1 is a front view of a guidewire for a medical device;

FIG. 2 is a rear view thereof;

FIG. 3 is a left-side view thereof;

FIG. 4 is a right-side view thereof;

FIG. 5 is a bottom view thereof; and,

FIG. 6 is a top view thereof.

The broken lines depict environmental subject matter only and form no part of the claimed design. The dot-dash lines depict a boundary between claimed and unclaimed surfaces, and form no part of the claimed design.
